UNITED STATES PATENT OFFICE

106,160

DESIGN FOR A PLATE OR SIMILAR ARTICLE

John Wadsworth, Penkhull, Stoke-on-Trent, England, assignor to Mintons, Limited, Stoke-on-Trent, England, a corporation of Great Britain

Application June 4, 1937, Serial No. 69,677
In Great Britain April 16, 1937

Term of patent 14 years

To all whom it may concern:

Be it known that I, John Wadsworth, a citizen of Great Britain, residing at 166 Trentham Road, Penkhull, Stoke-on-Trent, England, have invented a new, original, and ornamental Design for a Plate or Similar Article, of which the following is a specification, reference being had to the accompanying drawing, forming part thereof.

The drawing represents a plan view of a plate showing my new design, it being understood that the border decoration as shown in the drawing is continued around the border of the article.

I claim:

The ornamental design for a plate or similar article as shown and described.

JOHN WADSWORTH.
